UNITED STATES PATENT OFFICE.

ALLEN J. RHOADES, OF WEBSTER CITY, IOWA.

DESIGN FOR A RADIATOR ORNAMENT.

Application filed July 29, 1922. Serial No. 3,245. Term of patent 7 years.

To all whom it may concern:

Be it known that I, ALLEN J. RHOADES, a citizen of the United States, residing at Webster City, in the county of Hamilton and State of Iowa, have invented a new, original, and ornamental Design for Radiator Ornaments, of which the following is a specification, reference being had to the accompanying drawing, forming part thereof.

In the drawing,

Figure 1 is an elevation looking at the obverse side of the ornament, and

Figure 2 is a similar view looking at the reverse side of the ornament.

I claim:

The design for a radiator ornament, as shown.

ALLEN J. RHOADES.
